UNITED STATES PATENT OFFICE.

THOMAS R. CULVER, OF BRECKENRIDGE, TEXAS, ASSIGNOR OF THREE-SIXTEENTHS TO
E. J. HUNTER AND THREE-SIXTEENTHS TO R. E. BOWERS.

CHILD'S MOTOR CAR.

Application filed March 1, 1927. Serial No. 171,818.

This invention relates to toy motor cars and the general object of the invention is to provide a toy of this character which will run over a circular track and which may be 5 propelled by an electric motor.

A further object is to provide a construction of this kind which includes a car, preferably formed with two wheels disposed in tandem, and a radius rod or beam connected 10 at its outer end to the car and supported at its other end so as to rotate around a fixed center concentric to the track.

Another object is to provide means whereby electric current may be taken from a 15 house lighting system, carried to the center around which the car operates, and from thence carried by conductors supported on the radius rod or beam to the car motor.

Still another object is to provide means 20 whereby the circuit from the source of current to the motor may be broken in case the car should strike an object or a person and preferably provide means whereby a brake may be applied under this contingency.

A still further object is to provide like 25 means in connection with the radius rod or beam.

My invention is illustrated in the accompanying drawings wherein:—

30 Figure 1 is a top plan view of a motor car and track constructed in accordance with my invention;

Fig. 2 is a longitudinal horizontal sectional view of the motor car and a portion of the 35 track;

Fig. 3 is a vertical sectional view through the motor car;

Fig. 4 is a diagrammatic view of the wiring of the car and the means for conducting 40 electricity thereto;

Fig. 5 is a fragmentary section showing the details of the brake and circuit breaker and the latching means therefor.

Referring to these drawings and particularly to Figure 1, it will be seen that the track A may consist of concrete, wood, metal or any other suitable material arranged in a circle around a center. This track may be laid upon a lawn or form a permanent part 45 of a yard or garden. Operating on the track is the car 10 which may have any suitable form but is illustrated as approximating the form of a motor car and having a seat in its rear. I do not wish to be limited to the form 50 of car illustrated. This car is driven by a

driving wheel 11 mounted upon an axle 12. This driving wheel is shown at the middle of the car and at the forward end of the car is a skewed axle 13 having thereon the supporting wheel 14. This wheel 14 is disposed at 60 an angle to the longitudinal axis of the car so as to guide the car around the track. Both of these wheels 11 and 14 are preferably provided with rubber tires and may have a diameter of say 8". The motor 15 is preferably 65 an electric motor such as is used on washing machines and of any suitable horse power as, for instance, one-fourth horse power motor. The shaft of the motor carries on it the belt pulley 16 from which a 70 belt 17 transmits power to a belt pulley 18. The shaft of this pulley 18 carries upon it the pinion 19 which gears with a gear wheel 20, the shaft 21 of which carries the sprocket 75 wheel 22 over which a sprocket chain 23 passes which transmits power to a sprocket wheel 24 upon shaft 12, this wheel 24 being relatively small and the pinion 19 being relatively small in relation to the gear wheel 20 so as to multiply the speed transmitted from 80 the belt wheel 18. This belt wheel 18 is considerably larger than the belt wheel on the motor so as to reduce the speed of the motor. I do not wish to be limited to the particular 85 gearing or power transmitting mechanism.

The motor is operated by current taken from the house as will be hereafter described. The car is supported for movement around the center of the track by an arm or radius rod 25. This, as illustrated, extends 90 transversely of the car and is attached to the frame of the car in any suitable manner and is preferably hollow so that the electric wires by which current is conveyed to the motor may be carried therein. The inner end of 95 the arm is connected to a metal sleeve 26 rotating upon a metal post 27 which is embedded preferably in concrete at the center of the track, the sleeve being removable from the post. The sleeve may be of metal or insulating material and carries upon it two commutator rings 28 and 29 connected to the two wires which lead to and from the motor. Disposed parallel to the peripheral face of 100 the sleeve is a wooden or other post 30 which carries two contacts 31 engaging with the commutator rings and connected by suitable wiring to the house lighting system or to any other source of electricity.

Electrically connected to one of these rings 110

28 or 29 is a wire which leads into the motor and from the motor extends a return wire 33 which leads back through the arm 25 to the other commutator ring. A rheostat may be disposed in the circuit if desired to reduce or increase the current and thus secure a less or greater speed and as this is obvious, I have not illustrated any device of this character.

For the purpose of controlling the current, 10 I provide a control switch 34, which may be an ordinary knife switch, within the car toward the rear end thereof where it will be handy for the child operating the car; and for the purpose of automatically breaking a 15 circuit through the motor, if the car or the arm or rod 25 should strike a person or object, I provide a safety switch 35 in said circuit which is normally closed but which is opened to break the circuit under certain 20 circumstances. For the purpose of operating this switch I mount upon the forwardly projecting brackets 36 and the laterally projecting brackets 37, the flexible member 38 which may either have the form of a cable, 25 a wire, or a chain, though preferably it is in the form of a chain. The members 37 have eyes through which the chain 38 passes and the brackets 36 may have pulleys or eyes over or through which the member 38 passes. 30 One end of the chain 38 is rigidly connected to the car, as at 39. The other end of the chain passes through the eye 37 on that side of the car and then extends parallel to arm 25 and is connected at its outer end to said 35 arm in spaced relation thereto adjacent the rotative center of the arm. This chain is kept taut by any suitable means as, for instance, the spring 40.

I have heretofore referred to the chain 38 40 as being connected at 39 to a fixed point on the car. This chain at 39 is connected to a link 41 or equivalent member which in turn is connected to a bell crank lever 42 pivoted at 43. The switch 35 is connected by a loose 45 link chain 44 to the longitudinally extending rod 45 urged in a direction to open the switch by means of the spring 46. A vertically movable latch 47 engages a shoulder 48 on the head of rod 45 so that when this latch is 50 pulled down against the action of the spring 49 and by means of the bell crank lever 42, the rod 45 will move rearward, opening the switch and breaking the circuit. Pivoted to this rod 45 is a brake rod 50 which is 55 pivotally mounted at its lower end at 51 and carries the brake 52 which may engage with a brake drum 53 attached to the shaft of the main drive wheel in any suitable manner.

60 The rod 45 extends through the dash 54. It will be seen that contact by the chain with an object will place strain upon the chain which will cause the pulling down of the latch 47 and that immediately the spring 46 65 will cause the opening of switch 35 and the

application of the brake, cutting off the current. In order to close the circuit the rod 45 is pushed inward, causing a momentary depression of the latch 47 until the end of the latch slips by the head or shoulder 48 70 and this closes the switch 35 and, of course, releases the brake. It will be seen that this will occur upon the contact of an object or a person with the chain 38 at any point in the length of the chain so that thus the car will 75 be stopped either when the arm 25 or the car strikes an impediment. Preferably I contemplate that a bumper 55 having the appearance of a regulation automobile bumper shall be mounted upon the front of the 80 car on supports that will allow the bumper to move rearward under pressure, this bumper being connected by an arm or arms 56 with the chain 38 so that pressure against the bumper will cause the safety device to 85 operate. The rod 45 is mounted in suitable guides as, for instance, in guide brackets 57 mounted upon the frame or outside wall of the car. The push rod or link 41 may be either disposed beneath the car or operate 90 through the side of the car as desired.

While I have illustrated an automobile or the similitude of one, I do not wish to be limited to this as the same mechanism can be used in connection with a small platform 95 car having many seats or a car having the similitude of an animal thereon upon which children may ride. It is contemplated that the motor, gears, and wheels, may be assembled on a chassis or frame along the side of 100 the car giving ample leg room and I do not wish to be limited to the particular arrangement of the gearing illustrated. Variable speed may also be secured by using an obvious form of clutch and it is obvious 105 that a trailer can be attached in connection with the car and fixed in its path by one or more arms connected to the main radius arm 25.

I claim:—

1. A car, a radius arm having its outer end connected to the car and having its inner end mounted for rotary movement around a fixed center, an electric motor mounted on the car, means for transmitting current along the radius arm to said motor, and means for automatically breaking the circuit through the motor when the radius arm or car is about to strike an impediment. 115

2. A car, a radius arm having its outer end connected to the car and having its inner end mounted for rotary movement around a fixed center, an electric motor mounted on the car, means for transmitting current along the radius arm to said motor, and means for automatically breaking the circuit through the motor when the radius arm or car strikes an impediment including an inwardly contractible member mounted upon the forward end of the car and in 125 130

front of the radius arm, and a switch to which the member is connected.

3. A car, a radius arm having its outer end connected to the car and having its inner end mounted for rotary movement around a fixed center, an electric motor mounted on the car, means for transmitting current along the radius arm to said motor, and means for automatically breaking the circuit through the motor when the radius arm or car strikes an impediment including a flexible element supported in a taut condition in advance of the motor and radius arm and placed under strain on contact with

15 an impediment.

4. In a mechanism of the character described, a car, a radius arm to one end of which the car is connected, the inner end of the arm being mounted for pivotal movement, an electric motor mounted within the car, means for transmitting energy to the electric motor, a brake for the car, a switch for breaking the circuit through the motor, and means acting automatically to break the circuit through the motor and apply the brake as the car nears an impediment, and including a flexible element supported in a taut condition across the front of the car and in advance of the leading edge of the radius arm, the flexible element being operatively connected with the switch and the brake.

5. In a mechanism of the character described, a car, a radius arm upon which the car is mounted, the radius arm being pivoted for movement around a center, an electric

motor for the car, a brake for the car, a switch adapted to close or break the circuit through the motor, a longitudinally extending rod connected to the brake and to the 40 switch and in one position closing the switch and holding the brake out of operative position, means urging said rod into a position to apply the brake and open the switch, a latch normally holding the rod in the last 45 named position, and an impediment actuated member carried by the car and operatively connected to said latch to cause the release of the latch when the member strikes an impediment.

6. In a mechanism of the character described, a car, a radius arm upon which the car is mounted, the radius arm being pivoted for movement around a center, an electric motor for the car, a brake for the car, a 55 switch adapted to close or break the circuit through the motor, a longitudinally extending rod connected to the brake and to the switch and in one position closing the switch and holding the brake out of operative position, a spring urging said rod into a position to apply the brake and open the switch, a latch normally holding the rod in the last named position, an impediment-actuated member carried by the car and by the radius 60 arm in advance of the leading edge thereof and operatively connected to said latch to cause the release of the latch when the member strikes an impediment.

In testimony whereof I hereunto affix my 70 signature.

THOMAS R. CULVER.
